(57) **CLAIM**

The ornamental design for a pressure regulator for pneumatic jack, as shown and described.

DESCRIPTION

FIG. 1 is a top, front, right-side perspective view of a pressure regulator for pneumatic jack of the inventive subject matter.

FIG. 2 is a front view thereof;

FIG. 3 is a rear view of the thereof;

FIG. 4 is a left-side view thereof;

FIG. 5 is a right-side view thereof;

FIG. 6 is a top view thereof;

FIG. 7 is a bottom view thereof; and,

FIG. 8 is a bottom, rear, left-side view thereof.

Broken lines showing a hose as seen in FIGS. 1-2 and 4-7, broken lines showing a hole to receive a compressed gas as seen in FIGS. 3 and 8, broken lines showing lettering and arrows as seen in FIGS. 1 and 6, and broken lines showing a valve turning mechanism and a pressure regulator as seen in FIGS. 1-6 and 8 represent unclaimed portions of the design and form no part of the claimed design.
